UNITED STATES PATENT OFFICE.

VICTOR ANDERSON, OF NEW YORK, N. Y., ASSIGNOR TO WESTERN ELECTRIC COMPANY,
OF NEW YORK, N. Y., A CORPORATION OF ILLINOIS.

WELDED RECEIVER.

1,063,237.

Specification of Letters Patent.

Patented June 3, 1913.

Application filed April 3, 1912. Serial No. 688,200.

To all whom it may concern:

Be it known that I, VICTOR ANDERSON, a citizen of the United States, residing at New York, in the county of New York and State 5 of New York, have invented a certain new and useful Improvement in Welded Receivers, of which the following is a full, clear, concise, and exact description.

This invention relates to telephone receivers, more particularly to receivers of the bipolar type, in which the relation between the diaphragm and the pole pieces is such that it is impossible to throw them out of adjustment.

An object of this invention is to provide a magnet system for telephone receivers in which the use of bolts or rivets is avoided, all parts of the system being welded together.

Another object of this invention is to permanently attach the cup to the magnet system between the pole pieces and the magnet bars, the pole pieces and magnet bars being electrically welded together, and forming, with a cup, a unitary structure.

In the drawings—Figure 1 is a sectional view of a telephone receiver showing the spacing piece between the two bar magnets and the pole pieces welded to the end of the bar magnets and held spaced apart by the cup; Fig. 2 is a sectional view of the receiver taken at right angles to that of Fig. 1, showing the position of the coil on the pole piece and the connectors passing through the cup; Fig. 3 is a detail perspective view of the magnet system showing the manner of clamping the cup between the shoulders on the pole piece and the bar magnet.

Referring to the drawings, 10 and 11 designate two bar magnets spaced apart at their 40 rear end by the spacing piece 12, this spacing piece 12 being electrically welded to the bar magnets. At the forward end of the bar magnets 10 and 11 are electrically welded pole pieces 13 and 14 respectively. These 45 pole pieces are provided with a forwardly extending part 20 having shoulders 21 providing a stop for the energizing coils. The rear ends of the pole pieces are provided with an extending portion 22 having shoulders 23. The cup 24 is provided with perforations through which extend the portions

22 of the pole pieces. The pole pieces 13 and 14 are electrically welded to the bar magnets 10 and 11 respectively, thus clamping the cup 24 between the forward end of 55 the bar magnet and the shoulder 23 of the pole pieces. This arrangement insures that the distance between the pole pieces is maintained constant under all conditions of service.

Connectors 25 are shown passing through the cup 24 and insulated therefrom by the insulating bushing 26 and the insulating washer 27. The connectors are provided with a screw-threaded portion 28 on which 65 is screwed a nut 29 thereby clamping the connector firmly to the cup. A forward extension 30 is provided for the connector to which the terminal 31 of the energizing magnet 32 is attached. The connector is 70 provided with the usual binding screw 33 by means of which the usual leads are attached. The connectors are insulated from the magnet system by a fiber sheet 34.

The usual diaphragm 35 rests on the surface 36 of the cup 24 and in position to be acted on by the pole pieces 13 and 14.

The structure above described forms a unitary structure; that is, placed in usual receiver case 38 and clamped within the 80 case by the usual cap 37.

I claim:

1. In a telephone receiver, the combination of a magnet, a pole piece welded thereto, and a cup clamped between the pole piece 85 and the magnet.

2. In a telephone receiver, the combination of a magnet of the horse-shoe type, pole pieces for said magnet provided with shoulders, said pole pieces being welded to said 90 magnet, a cup clamped between the pole pieces and the magnet by the shoulders on the pole pieces, said cup holding the pole pieces in fixed relation to each other.

3. In a telephone receiver, in combination a cup, and a magnet having soft iron cores provided with shoulders, said cores extending through holes in the cup and being welded to the magnet, whereby the cup is clamped to the magnet by means of the shoulders on said cores.

4. In a telephone receiver, in combina-

tion, a magnet system comprising two bar magnets spaced apart, a spacing stud secured between the ends of the magnets, pole pieces for said bar magnets provided with shoulders, said pole pieces welded to the bar magnets at the end remote from the spacing stud, and a cup clamped between the shoulders on the pole pieces and the bar magnets

and acting as a spacing means for the pole pieces.

10

In witness whereof, I hereunto subscribe my name this first day of April A. D. 1912.

VICTOR ANDERSON.
